UNITED STATES PATENT OFFICE.

JOEL H. PAGE, OF PHILADELPHIA, PENNSYLVANIA, ASSIGNOR OF ONE-HALF
TO BLANCH CARRIE KING, OF SAME PLACE.

INDESTRUCTIBLE COMPOUND FOR COATING WIRES FOR ELECTRICAL PURPOSES.

SPECIFICATION forming part of Letters Patent No. 297,626, dated April 29, 1884.

Application filed December 28, 1883. (No specimens.)

To all whom it may concern:

Be it known that I, JOEL H. PAGE, a citizen of the United States, residing at the city of Philadelphia, in the county of Philadelphia, in the State of Pennsylvania, have invented a certain new and useful Improvement in an Indestructible Compound for Coating Wires for Electrical Purposes, of which the following is a specification, which will enable others skilled in the art to which it appertains to make and use the same.

My design is to produce, at very little cost, a means of protecting wires used for electric purposes, especially those used for underground purposes; and such means consist in embedding them in a moisture-proof, anti-induction, non-conducting compound, which, when hardened, will form a solid mass of wire and compound, thereby obviating the necessity of expensive leaden or other metallic means of protection, and which will cheaply protect the wires from any and all of underground influences which heretofore have prevented the general use of underground electric circuits, except at great expense.

To carry my invention into effect, I make a compound of the fused protoxide of lead, known to the arts as "litharge," and thoroughly incorporate with it a portion of glycerine barely sufficient to make of both a thick paste. The wires are then stretched the desired distance apart in a conduit or mold, and the com-

pound, in the form of a thick paste, is then poured upon the wires; and it is obvious that the paste will fill intervening spaces, and when hard will form a solid mass. Then the apparatus for separating the wires and keeping them taut can be moved, and the operation repeated.

I am well aware that a composition of the same materials has been already used as a joint-packing for vapor-engines, and that a composition of lamp-black, asbestos, litharge, and glycerine has before my invention been used for lining and coating pipes, tubes, cylinders, &c., and as a joint-packing; but I believe myself to be the first who has discovered that by coating wires intended for electric purposes with my almost inexpensive compound hereinbefore described a cheap and effectively-insulated electric wire is provided.

Having sufficiently set forth the mode of making and using my compound, I claim—

1. A compound of litharge and glycerine, formed into a thick paste, for coating wires to be used for electric purposes, substantially as hereinbefore described.
2. Electric wires coated with a compound of litharge and glycerine, substantially as set forth and described.

JOEL H. PAGE.
